(57) CLAIM

I claim the ornamental design for a teething bib, as shown and described.

DESCRIPTION

FIG. 1 is a perspective view of a teething bib showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines showing legible indicia in FIGS. 1 & 6 are understood to represent the portion of the design that forms no part of the claim.
